E. HOLMES

COMBING MACHINE

Filed March 21, 1923

INVENTOR:

By *Eugene Holmes*
Wm Wallace White
ATTY.

UNITED STATES PATENT OFFICE.

EUGENE HOLMES, OF MANCHESTER, ENGLAND.

COMBING MACHINE.

Application filed March 21, 1923. Serial No. 626,479.

To all whom it may concern:

Be it known that I, EUGENE HOLMES, a subject of the King of Great Britain, residing at 62 Clyde Road, West Didsbury, Manchester, in the county of Lancaster, England, have invented new and useful Improvements in or Relating to Combing Machines, of which the following is a specification.

The invention relates to improvements in or relating to combing machines.

In the lower end of the top nipper of a combing machine is usually provided a groove, or sometimes more than one groove, and in the working of the machine this groove usually becomes clogged or filled with dirt or dust which seriously detracts from the efficient working of the machine and much difficulty is experienced in cleaning this groove or grooves by reason of the fact that it cannot be seen and is difficult to reach.

Now the object of the present invention is to provide means whereby the top nipper may be turned up into such a position that said groove or grooves or the like is or are exposed to view so that it can be seen at a glance when the groove or grooves is or are clogged and thus said groove or grooves or the like is or are rendered easily accessible so that it or they can be cleaned with the minimum amount of trouble by the aid of a wire or other brush or other implement.

The accompanying drawing represents a diagrammatic view of the nipper arm, nippers and feed roller of a combing machine showing the application of the present invention to the top nipper.

Referring to said drawing, 1 represents the nipper arm, 2 represents the bottom nipper, 3 represents the feed roller and 4 represents the top nipper.

According to the present invention the nipper 4 or the carrier or fitting in which it is fixed or carried is pivotally mounted or

hinged at its upper end to the nipper arm 1 as shown at 5 so that said nipper 4 may be turned about said hinge 5 into the position shown by the dotted lines when the groove 4^a in the nipper, or there might be more than one groove, is exposed to view and readily accessible for cleaning purposes.

In order to fix the nipper 4 in its correct working position, that is to say, the position indicated by the full lines in the drawing, a suitable catch 6 of any suitable character, but preferably a spring latch, may be provided on the end of the nipper arm 1 with which latch the nipper 4 or the carrier or fitting in which the same is fixed may be engaged and retained in its proper working position.

It will be understood that the details of construction of the device may be modified without departing from the principle of the invention.

What I claim as my invention and desire to secure by Letters Patent is:—

1. In a combing machine, the combination of a nipper arm, a stationary bottom nipper, and a top nipper pivotally secured to said nipper arm and normally retained in contact with said bottom nipper, said top nipper being adapted to swing on its pivot away from the bottom nipper thereby to expose the underside of the top nipper.

2. In a combing machine, the combination of a nipper arm, a stationary bottom nipper, a top nipper pivotally secured to said nipper arm and normally in contact with said bottom nipper, said top nipper being adapted to swing on its pivot away from the bottom nipper thereby to expose the underside of the top nipper, and a spring latch for retaining the nippers in contact.

In testimony whereof I have signed my name to this specification.

EUGENE HOLMES.
